UNITED STATES PATENT OFFICE.

FRANCIS M. HANKS AND HORACE N. SIBLEY, OF MIDWAY, LOUISIANA.

SHINGLE-SAWING MACHINE.

SPECIFICATION forming part of Letters Patent No. 355,077, dated December 28, 1886.

Application filed June 18, 1886. Serial No. 205,546. (No model.)

To all whom it may concern:

Be it known that we, FRANCIS M. HANKS and HORACE N. SIBLEY, of Midway, in the parish of Bossier and State of Louisiana, have 5 invented a new and useful Band-Saw Shingle-Machine, of which the following is a full, clear, and exact description.

Our present invention relates to the construction of a band-saw shingle-machine designed more especially for use in connection with a band-saw—such as the one described, illustrated, and claimed in Letters Patent No. 336,407, granted to us on the 16th day of February, 1886; but the machine could be used 15 with a single-toothed band-saw, although not to so great advantage as with a double-toothed saw.

Reference is to be had to the accompanying drawings, forming a part of this specification, 20 in which similar figures of reference indicate corresponding parts in all the figures.

Figure 1 is a front view of our improved band-saw shingle-machine, the parts being broken away to disclose the construction. Fig. 25 2 is a side view of the machine. Fig. 3 is a sectional plan view of the machine with the reciprocating carriage removed. Fig. 4 is a sectional plan view of the carriage, taken on line *xx* of Fig. 2. Fig. 5 is a detail view illustrating the construction of the crank-adjusting attachment. Fig. 6 is a sectional plan view taken on line *yy* of Fig. 2, and Fig. 7 is a sectional elevation taken on line *zz* of Fig. 3.

In the drawings above referred to, 100 represents the main frame of the machine, in 35 which frame we mount the saw supporting and driving wheels 10, said wheels being mounted the one above and the other below a reciprocating carriage, 11, that is provided with wheels or 40 rollers 12, which ride on tracks or ways 13, that are supported by sills 14, carried by the main frame 100. In the peripheral face of each of the supporting-wheels 10 there are arranged yieldingly-mounted pins 15, which enter correspondingly-formed apertures or guiding-holes 2, that are formed at equal distances along the center line of the band-saw 20, so that the saw will be guided and held upon the upper transmitting-wheels 10, as is fully explained in our 45 patent above referred to. The lower wheel 10 is rigidly mounted upon the main driving-shaft 16 of the machine, and this shaft is

driven by a belt that passes over a pulley, 17, fixed to one end of said shaft. The shaft 16 carries a pinion, 18, that engages with a gear, 55 19, carried by a shaft 21, that is mounted in bearings that are in about the same plane as those employed to carry an adjustably-mounted shaft, 22, said shaft 22 being provided with a gear, 23, that is engaged and driven by a pinion, 24, that is carried by the shaft 21. The outer box of the shaft 22 is adjustable, and is guided by arms 25, formed in a bracket, 26, that is rigidly secured to the frame 100.

The bracket 26 is formed with a rearwardly-extending arm, 27, and to this arm there is pivotally connected a lever, 28, the short arm of which rests beneath the movable box or bearing of the shaft 22, upon the end of which shaft 22 there is a friction-pulley, 29, which 70 bears against the under face of a disk, 30, that is carried by a vertical shaft, 31, mounted in bearings 32, fixed to one end of the frame 100.

Upon the extending end of the long arm of the lever 28 there is a weight, 33, which may be 75 adjusted along the length of the lever, and so vary the pressure between the friction pulley or roller 29 and the disk 30; but when it is desired to lower the friction roller or pulley 29 from engagement with the under side of 80 the disk 30 the extending end of the lever 28 is raised through the medium of a lever, 34, that is formed with a shoulder, 35, which, when the lever 34 is thrown to a vertical position, will bear against the under side of the lever 85 28, and act to elevate the weight 33, thus permitting the movable end of the shaft 22 to drop, and thereby carry its pulley 29 from engagement with the disk 30.

Upon the top of the shaft 31 there is a block, 90 36, formed with ways 37, and in these ways there are mounted the arms 38 of a double-armed crank carrying the roller 39, which enters a slot, 40, formed in a projection, 41, that is rigidly secured to one end of the reciprocating carriage 11. To the opposite end of the arms 38 there is secured a plate, 42, formed with a central threaded socket, in which there is arranged a set-screw, 43, connected by a swivel-joint with the block 36, and formed 100 with an irregularly-shaped head, 44, adapted to fit within the socket of a crank-handle or key, so that the roller 39 may be adjusted toward or from the axis of the shaft 31, and thereby

decrease or lengthen the travel of the carriage 11, for, from the construction described, it will be seen that as the shaft 31 is rotated the carriage will be reciprocated—that is, driven 5 backward and forward over the ways 13—and it necessarily follows that the distance traveled will be governed directly by the length of the crank-arm.

The carriage 11 carries a frame, 50, in which 5 there are mounted two lower series of spur-rollers, 51, and two upper series of smaller spur-rollers, 52, said rollers being carried by shafts 53 and 54, respectively. The bearings of the shafts 53 are fixed; but the bearings of 5 the shafts 54 are arranged in movable blocks 56, that are suspended from the ends of rods 57, said rods being in turn connected to levers 58, mounted in brackets 59, arranged in the upper part of the frame 50, so that when necessary the rollers 52 may be elevated to permit of the introduction of the block from which the shingles are to be cut. The carriage 11 carries two rollers, 60, that are mounted upon the ends of springs 61, said springs being secured to the main body of the carriage, and being preferably of the form best shown in Fig. 2.

The rollers 60 serve to support the rear ends of the blocks to keep them from sagging, and 5 these blocks, from which the shingles are to be cut, are placed upon the spur-rollers 51, the rollers 52 being at this time lifted to permit of the introduction of the blocks; but after the blocks have been placed, as described, the 5 spur-rollers 52 are again lowered, so that they will rest upon the upper faces of the blocks that have been placed as described.

In order that the blocks may be fed forward, as desired, at each reciprocation of the carriage 11, we provide such a mechanism as will now be specifically described. To each side piece of the frame 50 there is pivotally connected a lever, 70, each lever carrying two pawls, 71 and 72, which pawls engage with 5 double ratchet-wheels 73 and 74, that are rigidly secured upon the extending ends of the shafts 53 and 54. The teeth of the upper and lower ratchet-wheels are arranged in opposition, and as the upper pawls, 71, are formed 5 with catch-teeth 3, which act to pull against the teeth of the ratchet-wheel 74, while the pawls 72 are arranged to push against the teeth of the ratchets 73, it follows that when the levers 70 are swung upon their pivotal connections 4 with the frame 50 the direction imparted to the spur-rollers 51 and 52 will be such as to feed the block forward both from above and below.

In order that the levers 70 may be reciprocated or rocked at each reciprocation of the carriage 11, we arrange them so that their lower ends extend downward through the platform of the carriage 11, and upon the lower ends of these levers we mount friction-rollers 5, which ride in S-shaped cam-grooves 80, that are formed upon the upper faces of the blocks 81, which blocks are carried by a horizontal and

double-threaded screw-shaft, 84, said shaft engaging with downwardly-extending bosses or lugs 85, that are centrally apertured and 7c threaded, in order that when the shaft 84 is turned the two blocks 81 will approach or separate, in accordance with the direction of rotation imparted to the shaft.

In operating the machine the length of the 75 crank by which the carriage is reciprocated and the position of the blocks 81 is adjusted, so that, although a shingle may be cut at each reciprocation of the carriage, the travel of the carriage will be only such as is required for 85 the sawing of the shingle of the width of the block employed.

In operation the blocks from which the shingles are to be cut are placed in the position described—that is, to fill the spaces A B 85 between the two sets of spur-rollers, the saw at this time being abreast of the central dividing-partition, 90. The machine is then started forward in the direction of the arrow No. 1, (shown in Fig. 1,) and a shingle or slab is 90 sawed from the block located at B—that is, from the block farthest removed from the roller 39, said block being previously set so as to come within the line of the teeth of the saw 20. As the carriage advances in the direction 95 of arrow No. 1 the roller 5, at the bottom of the forward lever, 70, enters its cam-groove 80, and the lever 70 is thrown in the direction of the arrow shown in connection therewith in Fig. 2, thus causing the block to be thrown 100 forward. When the carriage is driven back in the direction of arrow No. 2, the block located at A will be in the line of the teeth of the saw, and a slab or shingle will be sawed therefrom, and while the saw is acting upon 105 the block located at A the lever 70, arranged in connection with the spur-rollers, which hold the block at B, will, through the medium of its roller 5, be brought into engagement with the opposite cam-groove, 80, and the block located at B will be fed forward, and this operation is repeated indefinitely, the block at A being set while the block at B is in the path of the saw, and vice versa.

When it is desired to stop the reciprocating 115 motion of the carriage 11, the lever 34 is thrown in the direction of the arrow shown in Fig. 2, and the weighted end of the lever 28, being borne against by the shoulder 35, will be raised and the friction-roller 29 lowered from engagement with the disk 30, thus breaking the connection between the driving-shaft 16 and the vertical shaft 31, which carries the crank-arms by which the carriage 11 is reciprocated.

The blocks from which the shingles are cut 125 are adjusted so that the saw cuts parallel with instead of across the grain, as is usually the case, so that the shingles produced are free from cross-ridges, and will consequently last longer.

Having thus fully described our invention, what we claim as new, and desire to secure by Letters Patent, is—

1. The combination, with a doubled-toothed

- band-saw and its driving mechanism, of a reciprocating carriage carrying two sets of block-holders, two sets of set-works, and a mechanism, substantially as described, whereby one set of set-works is actuated to feed its block forward, while the block of the other set is operated upon by the saw, the same comprising levers with their lower ends actuated by oppositely-disposed cam-grooves, and which levers are each provided with pawls acting oppositely upon ratchets applied to the spur-roller shafts, substantially as described.
2. The combination, with a double-toothed band-saw and its driving mechanism, of a reciprocating carriage carrying two sets of spur-rollers and supporting-rollers and alternately-operating mechanism for rotating the spur-rollers, and mechanism for reciprocating the carriage, comprising a shaft carrying a disk engaging with the saw-driving mechanism, and the crank-arms connected to the said shaft and engaging a bracket of the reciprocating carriage, substantially as and for the purpose set forth.
3. The double-toothed band-saw, with its driving mechanism, the reciprocating carriage, carrying two sets of spur-rollers and supporting-rollers, the shaft carrying a disk engaging with the saw-driving mechanism, and the crank-arms connected to the said shaft and engaging a bracket of the saw-carriage, in combination with levers with their lower ends provided with rollers and actuated by oppositely-disposed cam-grooves, and which levers are each provided with pawls acting oppositely upon ratchets applied to the shafts of the spur-rollers, substantially as and for the purpose set forth.
4. The combination, with a double-toothed band-saw and its driving mechanism, of a reciprocating carriage carrying two sets of spur-rollers, 51 and 52, and spring supporting-rollers 60, levers 70, pawls 71 and 72, and ratchet-wheels 73 and 74, that are carried by the shafts of the spur-rollers 51 and 52, cam-grooves 80, arranged in the paths of the lower ends of the levers 70, and formed upon the upper faces of the blocks 81, that are adjustably mounted on a shaft, 84, and a mechanism, substantially as described, whereby a reciprocating-motion is imparted to the carriage, as and for the purpose specified.
5. The combination, with a band-saw and a reciprocating carriage carrying set-works, substantially as described, of a mechanism for imparting a reciprocating motion to the carriage, consisting, essentially, of a vertical shaft carrying a disk, 30, that is engaged by a friction roller or pulley, 29, crank-arms 38, and an adjusting-screw, 43, the crank-arms being provided with a roller, 39, that enters a groove formed in a bracket, 41, that is secured to the carriage, substantially as described.
